No. 36,962.

Patented June 14, 1904.

UNITED STATES PATENT OFFICE.

HARRY J. REYNOLDS, OF ST. LOUIS, MISSOURI.

DESIGN FOR A SOUVENIR-BRICK.

SPECIFICATION forming part of Design No. 36,962, dated June 14, 1904.

Application filed March 19, 1904. Serial No. 199,043. Term of patent 7 years.

To all whom it may concern:

Be it known that I, HARRY J. REYNOLDS, a citizen of the United States, residing at St. Louis, Missouri, have invented a certain new, original, and ornamental Design for a Souvenir-Brick, reference being had to the accompanying drawings, forming a part hereof.

Figure 1 is a perspective view of my souvenir-brick, showing the top, one end, and one edge thereof. Fig. 2 is a perspective view, showing the bottom, one end, and one edge thereof.

I claim—

The ornamental design for a souvenir-brick, as shown.

HARRY J. REYNOLDS.
